RECIPROCATING VARIABLE DELIVERY PUMP

Frederick Nettel, 173 Chapel Road, Manhasset, N.Y.

Filed Aug. 12, 1958, Ser. No. 754,613

5 Claims. (Cl. 103—41)

This invention deals with piston or plunger pumps, particularly to such employed for delivering fluids of any kind, as well as gases or vapors in variable quantities while operating at substantially constant speed.

Known pumps of this general performance either employ rather complicated variable-stroke devices (variable crank radius, swash plates etc.) or the start of delivery is more or less delayed, beginning at points where the piston has reached already appreciable or high velocities.

Special mechanical devices, as mentioned, are expensive to build and to maintain, while the sudden start of delivery when the piston is moving, involves heavy hydraulic shocks which under certain conditions may even prove destructive.

It is the principal object of this invention to eliminate these drawbacks and the possibility of leakage of fluids or gases outside the pump.

It is another object of this invention to provide a simple and cheap means for sensitive and fast regulation of fluid delivery at any operating speed, requiring a small actuating force.

It is a further object of my invention to provide a pump which may furnish two fluid streams of same or different pressures.

These and other objects and advantages of my invention will be apparent from the following specification when taken with the accompanying drawings, which show by way of non-limiting examples embodiments of my invention.

In the drawings, Fig. 1 is a diagrammatic section through a pump with liquid storage tank. Fig. 1a is a sectional view through the cylinder of the pump as per Fig. 1. Fig. 2 shows a modification depicting delivery control by a rotatable element. Fig. 3 indicates the design of the control sleeve for the pump as per Fig. 2. Fig. 4 shows the same control sleeve with the secondary piston in position for maximum delivery. Fig. 5 shows another embodiment of my invention avoiding a high pressure seal. Fig. 6 depicts the control sleeve used in pump as per Fig. 5.

The main object of my invention is achieved by the provision of a primary cylinder in which a primary piston is reciprocable, the piston being provided with an axially extending aperture or recess, called for the purposes of this specification hereinafter "secondary cylinder," the primary cylinder having an adjustable member, called hereinafter "secondary piston" adjustable relative to the secondary cylinder in such manner, that in accordance with the selected position of the secondary piston, effective fluid delivery will be terminated sooner or later during the working stroke of the primary piston.

Reverting now in more detail to Fig. 1: 1 indicates the body of a primary cylinder in which the primary piston 2 is reciprocable by the crank drive 3 with the stroke S. The primary piston 2 carries at its lower end piston rings 4 as seals, being connected to the crank drive by the wrist pin 5. The upper part of the piston 2 is provided with grooves 6 at its circumference which are connected to a

ring-shaped space 7 from which a bore 8 is connected via the vertical duct 9 to the suction valve 10 which seals off toward the secondary cylinder 11. This valve is disposed centrally within the primary piston. Screwed into 5 the secondary cylinder is a control sleeve 12, equipped with radial ports 13 arranged round its circumference. Mounted above the secondary cylinder, and adjustable by screw in the cover 14 of the primary cylinder, is the secondary piston 15 which is in axial alignment with the 10 control sleeve 12, closely fitting within the latter. The secondary piston has a central bore 16 which connects via a radial bore 17 with a cylindric space 18 in the cylinder cover 14 and thence with the fluid delivery conduit 19. The screw thread of the secondary piston 15 permits the latter to be moved vertically within the control sleeve 12 to any desired degree by the hand-wheel 20.

Interposed in the axial bore 16 is the delivery valve 21, as shown. The primary cylinder is connected via the pipe 20 21' with the fluid source, for example the tank 22.

Briefly stated, the pump operates as follows:

In Fig. 1 both the primary piston and the secondary piston are shown in their lowest positions. Due to the connection with the tank 22 all spaces within the pump 25 are assumed to be filled with fluid. If now the primary piston begins to rise, the ports 13 will be opened and establish connection between the secondary cylinder 11 and the primary cylinder 1, with the result that the whole content of the cylinder 11 is displaced back into the cylinder 1 and thence back into the tank 22. No appreciable pressure rise can take place within the cylinder 11, so that the valve 21 remains closed, and the delivery 30 of the pump is zero.

If now, for example, the secondary piston 15 is screwed 35 upward to a position higher by the stroke S, as indicated by the dash-dotted lines, the piston 15 will keep the ports 13 closed over the whole stroke, thus sealing the secondary cylinder 11 and forcing its contents under pressure out via the valve 21, the bores 16 and 17 and the delivery 40 conduit 19. This position of the piston 15 corresponds to maximum pump delivery.

Obviously, in any position of the secondary piston 15 between the two described above, the ports 13 will open 45 more or less before the primary piston reaches its uppermost position, thus terminating delivery earlier, so that the pump will furnish partial volumes, as desired.

At this point it is necessary to point out a vital difference between the mode of operation of known pumps and my invention: In known pumps the start of the delivery is delayed at the beginning of the working stroke so that, when the effective stroke begins, the piston 2 has already a considerable velocity relative to the piston 15, or its equivalent in other designs. Sudden sealing of the cylinder 11 causes under such circumstances a sudden 55 hydraulic shock which is most undesirable and may be destructive. Contrary to this, in applicant's pump, delivery always starts near the bottom dead center where the velocity of the piston 2 is practically zero. The ports 13 open to relieve the pressure within the cylinder 11 sooner 60 or later according to the adjustment of the piston 15, which takes place without shock and ensures smooth operation also at high speeds.

The seal between the piston 15 and the control sleeve 12 can be effected in any known manner, for example by 65 close metal-to-metal fit by lapping or piston rings, soft seals etc. Any leakage from the cylinder 11 will be into the cylinder 1, i.e. not outside the pump.

Fig. 1a shows a section through the pump as per Fig. 1 along the line A—A'. Parts corresponding to parts in 70 Fig. 1 are described in all figures by the same numerals.

Fig. 2 depicts an alternative embodiment in which no axial adjustment of the secondary piston is used, but in

which a rotary motion of this piston may achieve any pump delivery from zero to maximum. The cylinder part only is shown. In this case the primary and secondary cylinders are essentially the same as in Fig. 1, except that the ports in sleeve 12 are arranged in echelon around the sleeve circumference, preferably in such manner that the maximum difference in height of the ports corresponds to the stroke S, as shown. In Fig. 3 the sleeve 12 is shown removed from the pump. In this figure there is a second row of ports indicated which serves to increase the flow area between the primary and secondary cylinders. In Fig. 2 the secondary piston has its upper working edge cut at an angle to the horizontal which may be the same as the echelon angle at which the ports are disposed in the sleeve 12. The secondary piston has again a central bore 16 with an interposed delivery valve (not shown here), which ends at the delivery conduit 19. The shank of the piston 15 carries a flange 15' which bears against the cylinder cover 14, forming a thrust bearing for the piston 15. The pin 23 protrudes into a groove of the piston shank to prevent its being moved downward during the suction stroke.

In Fig. 2 the piston 2 is again drawn in its lowest position. Obviously, when it begins to rise, the ports 13 begin to be opened gradually, with the piston 15 in the position as shown, and the pump delivery is consequently zero. If now the piston 15 is turned around its axis by 180 degrees, it comes into the position as shown in Fig. 4. The ports 13 remain sealed by the piston 15 during the full working stroke and the pump delivery is at its maximum. If the piston is turned by angles smaller than 180 degrees, the ports will begin to open at different points during the working stroke so that partial deliveries can be adjusted at will by operating the handwheel 20.

Fig. 5 indicates a modification of the design of Fig. 2 in which the piston 15 consists of two parts, i.e. a center part 15 which is rigidly connected to the cylinder cover 14 and a rotatable sleeve 15" surrounding it which carries a recess forming a working edge identical with the upper working edge of the piston 15 in Fig. 2. The lower end of part 15 is of conical shape against which a cone provided at the lower end of the sleeve 15" is pressed during the delivery stroke of the pump, forming a tight seal against any pressure, while allowing the sleeve to be rotated. The sleeve 15" is prevented from moving downward during the suction stroke by the pin 23 protruding into a groove in part 15. This design has special merits for very high pressures and high capacities because any movable high-pressure seal is eliminated. Fig. 6 shows the sleeve 15" partly in section with a gear rim 24 at its upper end which may be arranged to be operated by hand or automatically through a conventional gear rack (not shown).

Reverting again to Fig. 2, attention is drawn to the spring loaded suction valve 10', and to the spring loaded delivery valve 21', both connected to the primary cylinder 2. The valve 10' is used where no fluid tank under static pressure is available, in which case the surplus intake fluid is discharged through the valve 21'. Obviously, it is possible to operate the pump of the primary cylinder and primary piston as separate pump of larger volume, with the secondary piston 15 set for zero delivery, for example. However, delivery of fluid can also take place simultaneously at 19 and through valve 21'. This may be advantageous in certain hydraulic drives where two separate pumps are now used, one for high pressure at small volume, the other at larger volume at lower pressure. The valves 10' and 21' can be used with any of the embodiments shown.

The suction valve 10 in Fig. 1 is shown without spring. While a spring can be used, it is not necessary, because due to inertia the valve will close during acceleration upwards and open during deceleration. During downward motion the action is, of course, reversed. This is advan-

tageous also for air or vapor pumps because the valve resistance is eliminated during the suction stroke.

It is immaterial for the purposes of this invention by what means the reciprocating motion of the pistons is effected: it may be by crank, cam, eccentric, swashplate, for examples. It is also irrelevant what types of valves are used and how many units of pumps are used together and how these units are arranged to each other.

While in the foregoing preferred embodiments of my invention have been described and shown, it is understood that further alterations and modifications may be made within the scope of the appended claims.

What I claim is:

1. In a reciprocating, constant speed, variable delivery pump for handling media such as fluids, gases or vapors comprising a source of such media, the combination of a primary cylinder, a primary piston disposed to operate reciprocably within said primary cylinder, a secondary cylinder centrally disposed and axially extending within said primary piston, a secondary piston extending into said primary cylinder in axial alignment with said secondary cylinder, said secondary cylinder disposed to operate reciprocably relative to said secondary piston, first conduit means for connecting the source of medium with the primary cylinder, an aperture between said primary and secondary cylinders, second conduit means for connecting said primary and secondary cylinders, a check valve interposed in said second conduit means permitting flow of medium from the primary cylinder into the secondary cylinder on movement of the secondary cylinder away from said secondary piston, an axial passage in the secondary piston extending through it and connecting the secondary cylinder with the outside, a check valve interposed in said passage permitting flow of medium from said secondary cylinder to the outside on movement of said secondary cylinder toward said secondary piston, said secondary piston being adjustable relative to said secondary cylinder for controllably opening said aperture between said primary and secondary cylinders at freely selectable points in the stroke of the secondary cylinder, the amount of medium displaced from said secondary cylinder to the outside during its movement toward said secondary piston being determined by specific position of adjustment of the latter.

2. Reciprocating pump as set forth in claim 1, having said aperture between the primary and secondary cylinders in the form of ports disposed around the circumference of the secondary cylinder, substantially in a plane at right angle to the axis of said secondary cylinder, and means to adjust the position of said secondary piston in the direction of its axis.

3. Reciprocating pump as set forth in claim 1, having said aperture between the primary and secondary cylinders in the form of ports disposed in echelon around the circumference of said secondary cylinder, said secondary piston having axial sealing contact with said secondary cylinder of varying lengths at different points along the circumference of said secondary piston, and means for turning the latter around its axis.

4. Reciprocating pump as set forth in claim 3, having rotatable sleeve means disposed around said secondary piston and forming part of it, said sleeve having axial contact with said secondary cylinder of varying lengths at different points along the circumference of said secondary sleeve and means for rotatably adjusting the position of said sleeve for controlling said aperture between the primary and secondary cylinders.

5. Reciprocating pump as set forth in claim 1, having a check valve interposed in said first conduit means permitting flow of medium from the source into the primary cylinder on movement of the primary piston out of the primary cylinder, third conduit means connecting the primary cylinder with the outside, a check valve interposed in said third conduit means permitting flow of

medium out of the primary cylinder on movement of the primary piston into the primary cylinder, to enable the primary cylinder with primary piston to act as pump independent of any pumping action taking place in the secondary cylinder.
